UNITED STATES PATENT OFFICE

97,946

DESIGN FOR AN AUTOMOBILE BUMPER

Jacob F. Martin, Bellevue, Ohio

Application September 16, 1935, Serial No. 58,573

Term of patent 3½ years

To all whom it may concern:

Be it known that I, Jacob F. Martin, a citizen of the United States of America, residing at Bellevue, Huron County, Ohio, have invented a new, original, and ornamental Design for an Automobile Bumper, of which the following is a specification, reference being had to the accompanying drawing, forming part thereof.

Fig. 1 is a front elevation of the automobile bumper embodying my new design, and the dominant feature of my design is shown in solid black lines;

Fig. 2 is an enlarged front elevation of an automobile bumper element shown in solid black lines in Fig. 1; and

Fig. 3 is a plan view of the automobile bumper element shown in solid black lines in Fig. 2.

I claim:

The ornamental design for an automobile bumper substantially as shown and described.

JACOB F. MARTIN.
